United States Patent Office

Des. 188,603

Patented Aug. 16, 1960

188,603

HOLDER FOR RECORD ALBUMS

Joseph C. Cavella, Chicago, Ill.

Filed Sept. 10, 1959, Ser. No. 57,509

Term of patent 7 years

(Cl. D33—3)

FIG. 1

FIG. 4

FIG. 2

The dotted lines in Fig. 2 are for illustrative purposes only and illustrate an album in position in the holder.

I claim:

The ornamental design for a holder for record albums, as shown and described.
